DESIGN FOR A RUG

George E. Mallinson, Amityville, N. Y.

Application July 17, 1937, Serial No. 70,496

Term of patent 3½ years

To all whom it may concern:

Be it known that I, George E. Mallinson, a citizen of the United States, residing at Amityville, county of Suffolk, and State of New York, have invented a new, original, and ornamental Design for a Rug, of which the following is a specification, reference being had to the accompanying drawing, forming part thereof, wherein—

The figure is a plan view of the lower one-half of the rug embodying my new design, the upper one-half being the same but in reverse order to complete the rug and terminating in a similar border to that shown.

I claim:

The ornamental design for a rug substantially as shown and described.

GEORGE E. MALLINSON.
